US0D1084996S

(12) **United States Design Patent** (10) **Patent No.:** **US D1,084,996 S**
(45) **Date of Patent:** **** Jul. 22, 2025**

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(73) Assignee: **Shenzhen Yifeng Intelligent Technology Co., Ltd.**, Shenzhen (CN)

(**) Term: **15 Years**

(21) Appl. No.: **29/909,310**

(22) Filed: **Aug. 3, 2023**

(30) **Foreign Application Priority Data**

Apr. 23, 2023 (CN) 202330227108.4

(51) **LOC (15) Cl.** **13-02**

(57)

CLAIM

The ornamental design for a wireless charger, as shown and described.

DESCRIPTION

FIG. 1 is a front perspective view of a wireless charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the wireless charger, that form no part of the claimed design.

1 Claim, 8 Drawing Sheets
